(57) **CLAIM**

The ornamental design for a keyed electrical connector, as shown and described.

DESCRIPTION

FIG. 1 is a perspective view of a keyed electrical connector showing my new design, the portion in phantom lines forming no part of the claimed invention;

FIG. 2 is a front view thereof;

FIG. 3 is a top view thereof, the bottom view being identical; and,

FIG. 4 is a side view thereof, the opposite side view being identical.
